LIQUID DISPENSING APPARATUS

Walter B. Williams, Glendale, Long Island, N. Y., assignor to Nu-Grain Co., Glendale, N. Y., a partnership composed of Walter B. Williams and Dorothy Walter

Application March 31, 1943, Serial No. 481,317

9 Claims. (Cl. 221—67)

The present invention relates to liquid dispensing apparatus and, more particularly, to such apparatus adapted for dispensing liquid material therefrom to a transfer member upon contact by the latter of dispensing mechanism of the former.

A general object of the present invention is the provision of such apparatus which is of simple and economical construction and which can be readily and easily employed to dispense to a transfer member, such as a brush, a controlled flow of a particular liquid, and which is adapted to ready adjustment and/or manipulation to alter the rate of flow as may be desired.

A more specific object of the invention is to provide such apparatus which is characterized by a container having a walled opening communicating with the interior thereof so supportable as to provide a head of contained liquid on the opening, a plug of porous absorbent elastic material positioned in the walled opening to close it while presenting its outward end for wiping engagement by a transfer member to dispense to the latter contained liquid with the plug sealingly engaging in an effective manner the wall of the opening for an appreciable depth, and an elongated member projecting from the opening with its inner end positioned at a desired depth between the plug and opening wall to provide an air passage between the two thereby to reduce in an efficient and simple manner the depth of the seal, the position of the member being readily alterable for desired adjustment of the depth of the seal.

A further object of the invention is the provision in such device of such seal breaking member to be operable as a valving member upon movement thereof by a transfer member to compress a portion of the elastic porous plug for reducing during such action the depth of seal between the plug and opening wall for obtaining in an efficient manner desired free flow of liquid being dispensed.

A still further object of the invention is the provision of such apparatus which is efficiently employable for controlled and constantly accessible supply of staining fluids in the brush application of stains to wood and the like such as in the decorating and graining of smoking pipe bowls.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had

to the following detailed description taken in connection with the accompanying drawing, in which:

Fig. 1 is a side elevational view of an embodiment of the present invention showing the same charged with a body of liquid material and in dispensing position;

Fig. 2 is a sectional view taken on line 2—2 of Fig. 1;

Fig. 3 is a fragmentary enlarged sectional view with parts in section, taken substantially along line 3—3 of Fig. 2, of the dispensing portion of the structure shown in Fig. 1, indicating the operational functioning of parts during a valving action; and

Fig. 4 is a plan view of a preferred form of air-bleeding and valving member employed in the embodiment shown in Figs. 1 to 3, inclusive.

Referring to the drawing, in which like parts are identified by like characters throughout, an embodiment of the invention as therein shown may comprise a suitable container, such as a bottle 10, having a walled opening communicating with the interior thereof, such as a neck 11, preferably provided with external threads 12 for engagement by a covering cap to close the device when not in use. The inner wall of the neck 11 is identified by reference numeral 13.

A plug 14 of porous absorbent elastic material, such as sponge rubber, is confined within the neck 11 preferably in a partially compressed condition so as to assure an efficient seal between it and the wall 13. This plug preferably has its outer end 15 projecting at least a small distance from the end of the neck 11 to assure free access thereto by means of a transfer member such as a brush.

An air-bleeding and valving member 16 may comprise a bar of rigid material but in the preferred embodiment consists of a U-shaped relatively rigid member having legs 17, 17 thereof positioned between the plug 14 and the wall 13 a predetermined distance extending to, for example, a point 18 as indicated in Fig. 3 thereby breaking the seal to such point and providing therewith air bleeding passages 19—19 as indicated in Fig. 2. As a result the depth of seal between the plug 14 and the wall 13 is reduced to a distance, say that indicated at 20 in Fig. 3, and obviously this distance may be varied at will by positioning the member 16 farther into the neck 11 or withdrawing it to a desired extent. This is important for adjustment of delivery of contained liquid material, the rate of which is dependent upon the head of contained liquid on the walled opening, the porosity of the plug, depth of seal between the plug 14 and the wall 13 and the characteristics thereof, the latter also being in part dependent upon the degree of compression of the plug and inherent recovery char-

acteristics of the material from which the plug is made. It will thus be seen that this structure provides a ready means for adjustment of flow to suit a particular set of conditions. Since, taking into account rate of evaporation of a particular liquid to be delivered, it is desired that the face of the projecting end 15 of the plug during use be at all times moist and capable of delivering to a transfer member, such as a brush a predetermined amount of liquid without excessive delivery resulting in dripping of the liquid upon supporting structure.

Additional functioning of the delivery mechanism will be indicated in connection with the following outline of operation. The container 10 15 may suitably be provided with a body 21 of liquid material, such as stain or the like, and the container may suitably be supported upon a base 22 by any suitable means to provide a head on the opening, such as by inversion to the position indicated in Fig. 1 and so mounted by any suitable means, such as support 23 and a pair of legs 24, 24 fastened on opposite sides of the neck 11 to a surrounding band 25. The opening will previously be closed by the plug of porous absorbent elastic material 14 compressed and forced into the neck 11 to provide a depth of sealing engagement between the plug 14 and the wall 13, such as that indicated at 26 in Fig. 3. The member 16 is to be inserted between the plug 14 and the wall 13 to a desired depth, such as to the point 18, the legs 17, 17 of the member 16 being held securely in position between the plug 14 and wall 13 by reason of the resiliency of the plug material and providing passages 19-19. The depth of insertion of the member 16 may be readily adjusted at will to provide a certain rate of flow.

If such adjustment proves to be not quite adequate to give a desired rate of flow or if after a certain amount of liquid material has been withdrawn from the container so that the head of liquid material upon the opening is reduced to such an extent as materially to slow up the rate of flow, a freer flow of liquid may be obtained by depressing the projecting end of the member 16, for example, by fulcrumming it about line 27 at the lip of the neck from the dotted line position to the full line position shown in Fig. 3. This can readily be accomplished by means of the transfer member such as a brush 28 and the outer end of member 16 may be depressed thereby one or more times if desired. Depression of the projecting end of the member 16 causes the inserted legs thereof to be raised to the full line position shown in Fig. 3 depressing the adjacent material of the plug 14, the outer surface of which will assume a shape such as that indicated at 29 thereby reducing the depth of seal a distance such as that indicated at 30. In addition compression of the plug material by such action of the member 16 will cause liquid contained in the pores thereof to be squeezed out to the face 15 and continuation of such action or jiggling of the member 16 will cause it to act as a valving member with attendant pumping action since upon release of the compressed plug body to its original position expansion will create a partial vacuum in pores thereof to draw additional liquid into the body and subsequent depression will force the contained liquid out toward the face 15.

In the employment of the device of the present invention for controlled delivery of stain material for the decorating and graining of pipe bowls and the like, the artist finds available at the exposed face 15 of the plug 14 a continual

supply of stain to be picked up by a transfer member, such as a brush 27, when the bristles thereof are wiped across the face 15. The device of the present invention has proven to be exceptionally advantageous for this purpose.

It is to be understood that the shape of the air and/or liquid bleeding and valving member 16 is not limited to the shape shown by way of example in the drawing since obviously it may comprise a single rod or a flat piece, the form shown being preferred because of its ready adaptation to the provision of a plurality of air and/or liquid bleeding passages 19-19 by a single rigid construction which is readily and economically manufactured. It will further be understood that the apparatus is not limited to the employment of the type of container shown since any form of container which provides a suitable head of contained liquid on a walled opening to be plugged in accordance with the teachings of the present invention will satisfy the requirements, suitable provision, of course, being made for freedom of action of the projecting member 16.

It will thus be seen that the objects set forth above, among others apparent from the above disclosure, are attained in an efficient manner and since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A liquid dispensing device comprising a container having a walled opening communicating with the interior thereof, means to support said container in a position providing a head of contained liquid on the opening, a plug of porous absorbent elastic material confined within the walled opening to close the same and having an end thereof exposed to provide a dispensing face for wiping engagement by a transfer member, said plug sealingly engaging the wall of said opening for an appreciable depth, and an elongated member projecting from the opening and having an end adjustably positioned between the wall of the opening and said plug a predetermined distance to provide a passage between said plug and opening wall thereby to reduce the depth of the seal therebetween.

2. A liquid dispensing device comprising a container having a walled opening communicating with the interior thereof, means to support said container in a position providing a head of contained liquid on the opening, a plug of porous absorbent elastic material confined within the walled opening to close the same and having an end thereof exposed to provide a dispensing face for wiping engagement by a transfer member, said plug sealingly engaging the wall of said opening for an appreciable depth, and an elongated member projecting from the opening and having an end adjustably positioned between the wall of the opening and said plug a predetermined distance to provide a valving member which upon movement by contact with a transfer member

compresses said plug to reduce the depth of the seal for freer flow of liquid.

3. A liquid dispensing device comprising a container having a walled opening communicating with the interior thereof, means to support said container in a position providing a head of contained liquid on the opening, a plug of porous absorbent elastic material confined within the walled opening to close the same and having an end thereof exposed to provide a dispensing face for wiping engagement by a transfer member, said plug sealingly engaging the wall of said opening for an appreciable depth, and an elongated member projecting from the opening and having an end adjustably positioned between the wall of the opening and said plug a predetermined distance to provide a passage between said plug and opening wall thereby to reduce the depth of the seal therebetween and to provide a valving member which upon movement by contact with a transfer member compresses said plug further to reduce the depth of the seal for freer flow of liquid.

4. A liquid dispensing device comprising a container having a walled opening communicating with the interior thereof, means to support said container in a position providing a head of contained liquid on the opening, a plug of sponge rubber confined within the walled opening to close the same and having an end thereof exposed to provide a dispensing face for wiping engagement by a transfer member, said plug sealingly engaging the wall of said opening for an appreciable depth, and an elongated member projecting from the opening and having an end adjustably positioned between the wall of the opening and said plug a predetermined distance to provide a passage between said plug and opening wall thereby to reduce the depth of the seal therebetween.

5. A liquid dispensing device comprising a container having a walled opening communicating with the interior thereof, means to support said container in a position providing a head of contained liquid on the opening, a plug of sponge rubber confined within the walled opening to close the same and having an end thereof exposed to provide a dispensing face for wiping engagement by a transfer member, said plug sealingly engaging the wall of said opening for an appreciable depth, and an elongated member projecting from the opening and having an end adjustably positioned between the wall of the opening and said plug a predetermined distance to provide an air passage between said plug and opening wall thereby to reduce the depth of the seal therebetween and to provide a valving member which upon movement by contact with a transfer member compresses said plug further to reduce the depth of the seal for freer flow of liquid.

6. A liquid dispensing device comprising a container having a walled opening communicating with the interior thereof, means to support said container in a position providing a head of contained liquid on the opening, a plug of porous absorbent elastic material confined within the walled opening to close the same and having an end thereof exposed to provide a dispensing face for wiping engagement by a transfer member, said plug sealingly engaging the wall of said opening for an appreciable depth, and an elongated U-shaped member having the legs thereof adjustably positioned between the wall of the opening and said plug a predetermined distance to provide a passage between said plug and opening wall thereby to reduce the depth of the seal therebetween.

of the opening and said plug a predetermined distance to provide passages between said plug and opening wall thereby to reduce the depth of the seal therebetween.

5 7. A liquid dispensing device comprising a container having a walled opening communicating with the interior thereof, means to support said container in a position providing a head of contained liquid on the opening, a plug of porous absorbent elastic material confined within the walled opening to close the same and having an end thereof exposed to provide a dispensing face for wiping engagement by a transfer member, said plug sealingly engaging the wall of said opening for an appreciable depth, and an elongated U-shaped member having the legs thereof adjustably positioned between the wall of the opening and said plug a predetermined distance, the bent portion of said member projecting beyond the dispensing face of said plug to provide a valving member which upon movement by contact between the projecting portion of said member and a transfer member compresses said plug to reduce the depth of the seal for freer flow of liquid.

8. A liquid dispensing device comprising a container having a walled opening communicating with the interior thereof, means to support said container in a position providing a head of contained liquid on the opening, a plug of porous absorbent elastic material confined within the walled opening to close the same and having an end thereof exposed to provide a dispensing face for wiping engagement by a transfer member, said plug sealingly engaging the wall of said opening for an appreciable depth, and an elongated U-shaped member having the legs thereof adjustably positioned between the wall of the opening and said plug a predetermined distance to provide a valving member which upon movement by contact between the projecting portion of said member and a transfer member compresses said plug to reduce the depth of the seal for freer flow of liquid.

40 9. A liquid dispensing device comprising a container having a walled opening communicating with the interior thereof, means to support said container in a position providing a head of contained liquid on the opening, a plug of sponge rubber confined within the walled opening to close the same and having an end thereof exposed to provide a dispensing face for wiping engagement by a transfer member, said plug sealingly engaging the wall of said opening for an appreciable depth, and an elongated U-shaped member having the legs thereof adjustably positioned between the wall of the opening and said plug a predetermined distance to provide passages between said plug and opening wall thereby to reduce the depth of the seal therebetween with the bent portion of said member projecting beyond the dispensing face of said plug to provide a valving member which upon movement by contact between the projecting portion of said member and a transfer member compresses said plug further to reduce the depth of the seal for freer flow of liquid.
